UNITED STATES PATENT OFFICE.

OBED CHARLES HAWKES, OF BIRMINGHAM, COUNTY OF WARWICK,
ENGLAND.

DESIGN FOR BEVELED GLASS.

SPECIFICATION forming part of Design No. 18,696, dated October 23, 1888.

Application filed July 11, 1888. Serial No. 279,671. Term of patent 14 years.

To all whom it may concern:

Be it known that I, OBED CHARLES HAWKES, a subject of the Queen of Great Britain, residing at Birmingham, in the county of Warwick, 5 England, have invented and produced a new and original Design for Beveled Glass, of which the following is a specification, reference being had to the accompanying drawings, forming part thereof.

10 The leading feature of my design for beveled glass is a rim with bevels in different planes or angles.

Figure 1 represents a section of a piece of beveled glass embodying my invention. Fig. 15 2 represents a face view thereof.

In the drawings, A represents a piece of glass having a rim, a, formed of bevels b c d in different planes or angles, the planes of each successive face from the lowermost upward

being at a less angle to the plane of the face 20 of the glass than the one preceding it, and the lines of their contact edges on opposite sides of the respective planes are parallel with each other.

I claim—

25 The design for beveled glass, as herein described and shown, consisting of a beveled rim having thereon successive faces, the planes of each from the lowermost being at a different angle to the plane of the glass from the 30 one preceding, and the said faces having on opposite sides the lines of the adjacent or contact edges parallel with each other.

OBED CHARLES HAWKES.
